CLAIM

The ornamental design for a hair braiding device, as shown and described.

DESCRIPTION

FIG. 1 is a perspective view of a hair braiding device showing my new design;

FIG. 2 is a front elevation view thereof;

FIG. 3 is a top plan view thereof;

FIG. 4 is a right side elevation view thereof;

FIG. 5 is a rear elevation view thereof;

FIG. 6 is a left side elevation view thereof;

FIG. 7 is a bottom plan view thereof; and,

FIG. 8 is a front elevational view of a second modified embodiment, the side opposite being a mirror image of the side shown, and the undisclosed edges being of the same uniform thickness as the first disclosed embodiment.
